E. P. LE COMpte,
FIRE STARTER.
APPLICATION FILED FEB. 12, 1918.

1,295,907.

Patented Mar. 4, 1919.

Inventor

Edward P. LeCompte,
By William O'Dane,
his Attorney

UNITED STATES PATENT OFFICE.

EDWARD P. LE COMPTÉ, OF PARK CITY, UTAH.

FIRE-STARTER.

1,295,907.

Specification of Letters Patent.

Patented Mar. 4, 1919.

Application filed February 12, 1918. Serial No. 216,710.

To all whom it may concern:

Be it known that I, EDWARD P. LE COMPTÉ, citizen of the United States, residing at Park City, in the county of Summit 5 and State of Utah, have invented certain new and useful Improvements in Fire-Starters, of which the following is a specification.

My present invention has to do with the 10 starting of fires in stoves and the like.

The general object of the invention is to provide a fire starting device possessed of the capacity of starting a coal fire without the employment of kindling wood, this being 15 materially advantageous because of the scarcity and high price of kindling wood.

Another object of the invention is the provision of a fire starting device embodying means for supplying an ample volume of 20 air under pressure to a fire with a view to promoting combustion, in combination with means for impregnating the air *en route* with a suitable hydrocarbon such as gasoline or kerosene in order to assure expeditious and thorough starting of the fire.

Another object is the provision of a fire starting device embodying electrical ignition means at the forward end of the device, in combination with means for supplying 30 commingled air and hydrocarbon to said point, this in order to render it unnecessary for the operator to place his or her hand in the fire box of a stove or the like and also in order to render it unnecessary to employ 35 kindling wood in the starting of the fire; the ignition means being preferably in the form of a resistance coil and being, therefore, well adapted to bring about the ignition of the paper or shavings employed especially 40 when the same are supplied with the hydrocarbon and also adapted to assist in the firing of the coal.

A further object is the provision of a fire starting device that is susceptible of being 45 conveniently handled or manipulated and operated with but little effort to produce a large volume of air under pressure, and one embodying means whereby its nozzle portion may be adjusted independently of its 50 body or major portion in order that the operator may start a fire at several points in succession in a fire box and thereby quickly bring about the firing of coal throughout the area of the fire box.

Other objects and points of practical advantage peculiar to my novel device will be 55 fully understood from the following description and claims when the same are read in connection with the drawings, accompanying and forming part of this specification, in which:

Figure 1 is a perspective view of the starter showing the application.

Fig. 2 is a side elevation partly in section to more clearly show the igniter.

Similar numerals of reference designate corresponding parts in all of the views of the drawings.

Among other elements my novel fire starting device comprises a combined body and 70 fan-blower casing 1, made of suitable sheet metal for the sake of lightness and having air-induction openings 2 in its side walls. The said body and casing 1 is provided with a forwardly-directed and tapered discharge 75 trunk 3, and is preferably, though not necessarily, equipped with suitable legs 4, such as illustrated so that it may be rested on a floor in front of the stove in which the fire is to be started.

The device also comprises a nozzle portion 5 arranged in front of and in spaced relation to the trunk 3 as shown; said nozzle portion being formed of metal or other material capable of resisting the action of fire. 85 The said nozzle portion 5 is adapted to be inserted into a fire box in close proximity to and preferably with its forward end in shavings or paper placed below coal when the fire is laid; and it is joined to the forward end of the trunk through the medium of a flexible conduit section 6 which is preferably of rubber or analogous material. It will be understood in this connection that the nozzle portion 5 is sufficiently long to 95 preclude the conduit section 6 being injured by heat or fire; also, that the said conduit section 6 is calculated to permit of the nozzle portion 5 being swung relatively to the trunk 3 so that without movement of the 100 major portion of the device, the nozzle portion 5 may be directed to different points in a fire box as occasion demands.

At 7 on the forward portion of the nozzle 5 is the electrical ignition means. This 105 means in the present and preferred embodiment of my invention is a resistance coil, as illustrated, and is made heavy in order to

withstand the usage to which appliances used about stoves and furnaces are ordinarily subjected. The said ignition means is connected through suitable wiring 8, 5 which extends as shown from the rear end of the casing body 1, with a terminal plug 9, designed to be placed in an electrical socket such as usually provided in residences so as to electrically connect the said ignition 10 means 7 with the house wiring. A switch 10 is preferably interposed in the wiring 8 and supported on the rear portion of the casing body as shown so that the operator of the fire starter may conveniently control 15 the supply of current to the ignition means 7. Manifestly when the proper electrical connections are established the operator by manipulating the switch 10 may cause the ignition means to glow or may render the 20 same idle at will.

Suitably affixed to and supported on the casing body 1 and the rear portion of the trunk 3 is a hydrocarbon reservoir 11 having a suitable closure 12 at its upper end. 25 The said hydrocarbon reservoir is provided at its lower end with a minute discharge 13, preferably controlled by a valve 14, and arranged in communication with the interior of the rear portion. Thus when the valve 30 14 is open to a greater or less degree and a volume of air is being forced forwardly through the trunk 3 the said air will be adequately impregnated with the hydrocarbon; the air operating by suction to take up the 35 hydrocarbon and to carry it to the discharge end of the nozzle 5. In this connection it will be noticed that I prefer to provide the forward portion of the nozzle 5 with a plurality of apertures 15 for the lateral discharge of the commingled air and hydrocarbon, this being especially advantageous in the event of the forward end of the said nozzle 5 being clogged by shavings or paper.

Arranged in the casing body 1 and fixed 45 to a transverse shaft 16 journaled in said casing body is a fan-blower 17, and for the purpose of rotating the said fan-blower at a high rate of speed and with the expenditure of but little effort on the part of the 50 operator I prefer to employ the following driving train, viz.: a pinion 18 fixed on the shaft 16, a large spur-gear 19 mounted on the casing body 1 and intermeshed with the pinion 18, a second pinion 20 intermeshed 55 with and adapted to drive the gear 19 and also mounted on the casing body 1, a pinion 21 fixed to and rotatable with the pinion 20, and a large internally-toothed gear 22 suitably mounted on the casing body 1 and in- 60 termeshed with the pinion 21; said gear 22 being, by preference, equipped with a handle 23. Manifestly when the operator rotates the gear 22 the fan blower 17 will be rotated at a high rate of speed, and a great

volume of air under pressure will be forced 65 through the trunk 3 and nozzle 5.

The practical operation of my novel device is as follows:

A fire is laid in a fire box with coal superimposed on an adequate quantity of shavings or paper or the like, and the nozzle 5 is inserted in the fire box to a point within the shavings or paper. The switch 10 is then manipulated to supply current to the ignition means, and the fan-blower is put in 75 operation, whereupon air impregnated with hydrocarbon such as gasoline or kerosene will be supplied to the paper or shavings and the same will be lighted by the ignition means and the fire caused to intensely burn. 80 The supply of air commingled with hydrocarbon is maintained until the burning of the coal or other hard fuel is well established, and when necessary the current may be supplied to the ignition means 7 until 85 the burning of the hard fuel is in progress, this because when the ignition means is in the preferred form of a resistance coil it alone will promote the burning of the hard fuel. It will also be understood from the 90 foregoing that the nozzle 5 and the ignition means 7 may be used to advantage when they are disposed under and in close proximity to a grate.

I have specifically described the construction and relative arrangement of the parts embraced in the present embodiment of my invention in order to impart a full, clear and exact understanding of said embodiment. I do not desire, however, to be understood as confining myself to the said specific construction and relative arrangement of the parts inasmuch as in the future practice of the invention such changes or modifications may be made as fairly fall within 95 the scope of my appended claims.

Having described my invention, what I claim and desire to secure by Letters Patent, is:

1. A fire starter, comprising a rotary 110 blower including a casing having a trunk, a tubular nozzle attached to the trunk and provided near its free end with outlet apertures formed in the side wall thereof, a liquid hydrocarbon supply device leading into 115 the trunk, and an electric resistance coil wound about the apertured end of the nozzle and disposed adjacent said apertures, the coil serving to heat the free end of the nozzle and the carbureted air discharging 120 through the apertures to ignite the same.

2. A fire starter, comprising a rotary 125 blower including a casing having a trunk, a tubular nozzle attached to the trunk and provided near its free end with outlet apertures formed in the side wall thereof, a liquid hydrocarbon holding tank secured to the casing and arranged above the trunk

and having an outlet opening to discharge the liquid hydrocarbon by gravity into the trunk, a manually operated valve to control the passage of the liquid hydrocarbon 5 through the outlet opening, and an electric resistance coil wound upon the exterior of the apertured end of the nozzle and disposed adjacent to said apertures, the coil serving to heat the nozzle and the carbureted air discharging through said apertures to ignite the same.

In testimony whereof I affix my signature in presence of two witnesses.

EDWARD P. LE COMPTE.
